LINING-GUN NOZZLE

Application filed December 14, 1928, Serial No. 326,145, and in Australia November 9, 1928.

This invention relates to a lining gun nozzle for lining either mouldings or plain surfaces upon motor cars and elsewhere, and it embodies a specially shaped and constructed body upon the end of a tapered tubular intake stem adapted to be secured by its larger end by means of a locking nut or other device to the gun. The specially shaped body is designed to be drawn along the moulding, and 10 its trailing edge is made more or less concave to conform approximately to the shape of the moulding. Within the body and running from top to bottom of same is a bore or passage which communicates on the one hand 15 with the intake stem and on the other hand by ducts with a series of countersunk openings along the face of the body and adjacent to the trailing edge of same, the countersink of each opening being extended to such edge. 20 Over such openings is a thin covering of fine hair the butt ends of the hairs being held to the body of the nozzle by means of a cover plate of spring steel and the operative or trailing ends of the hairs overlapping the 25 curved trailing edge of the body, the hairs at the centre being longer than those at the two ends.

In order that our invention may be the more clearly understood we will describe the same 30 with reference to the accompanying drawings in which

Fig. 1 is a view of a nozzle complete showing the operative face of same, that is to say the face which is laid against the moulding or 35 surface to be painted.

Fig. 2 is a similar view but with the hair, the spring steel cover plate and the drip container removed.

Fig. 3 is a section on line 3—3 of Fig. 1. 40 Fig. 4 shows the covering of hair held in its special mounting before being clamped in the nozzle.

As shown in the drawings 1 represents the tapered tubular intake stem having upon its 45 larger end a collar 2 whereby the nozzle is secured by means of a locking nut or other device to the gun.

3 represents the body within which is a bore or passage 4 which communicates with 50 the smaller end of the intake stem 1. The

bore or passage is preferably formed by drilling a hole right through the body from top to bottom and closing the ends of same by means of two plugs. This is especially convenient for cleaning purposes.

5 represents the trailing or operative edge of the body which is curved to more or less conform to the shape of the moulding to be lined. Along the face of the body and adjacent to this edge 5 are a series of countersunk 55 openings 6 each of which communicates by means of a small duct 7 with the bore 4 and each of which has a small extension 8 running out through the edge 5. The openings within the lower part of the body (the lower part when in use and as represented in the drawings) are smaller than those within the upper part for the purpose of regulating the flow of the lining liquid.

10 represents the covering of fine hairs 70 which are laid over the openings 6 and are held in place by means of a cover plate 11 of spring steel, preferably a piece of clock spring, which is attached to the body by means of two setscrews 12, one at either end. The covering of hair is prepared preferably by laying the butt ends of the hair upon a strip of adhesive tape and then covering same with a second strip of tape, after which the operative ends of the hairs are trimmed to the desired length. This forms a brush or pencil 75 as shown in Fig. 4. The hairs thus held together are laid upon the face of the body with the edge of the tape immediately against the leading edge of the body; the cover plate 11 is laid over them and secured in place by means of the setscrews 12 and the tape is then cut off.

Attached to the lower end of the body is a drip container 15 the stem 16 of which fits 80 into a socket or recess beneath the cover plate 11 and is perforated to take one of the setscrews 12 which holds the same in place.

Our nozzle may be used upon a lining gun of the usual type provided with plunger and trigger whereby the flow of the liquid may be controlled.

In use the face of the body is placed against the moulding and drawn along same. The lining liquid flows from the gun through the 85 100

tapered stem 1 into the bore 4 and thence through the openings 6 and along the hair 10 on to the moulding. Any surplus liquid passes down the stem 16 into the container 15. Although specially designed for lining mouldings our nozzle may be used for lining flat or other plain surfaces.

What we claim is—

1. A lining gun nozzle comprising an elongated flattened body upon the smaller end of a tapered tubular intake stem the larger end of which is adapted to be secured by means of a suitable device to the gun, a bore within the body and communicating with the intake stem, a series of countersunk openings along a face of the body and adjacent to an edge of same each of which communicates with the said channel and each of which is extended to the edge of the face, and a covering of fine hair held over such openings by a suitable clamping device.
2. A lining gun nozzle embodying an elongated flattened body upon one end of a tapered tubular intake stem, such body having within it a bore which communicates with the tubular intake stem and by means of ducts with a series of countersunk openings arranged along a face of the body and adjacent to an edge of same which countersunk openings extend to said edge of the body for the purpose set forth.
3. A device of the character described, comprising a body having a concave front face and provided with a longitudinal bore, a series of countersunk openings between the bore and the front face of the body, and ducts leading from the openings into the bore and through the concave face of the body, a brush body secured to the body over said openings and extending beyond the concave face of the body and having a working face curved reversely to the curvature of the face of the body, and an intake stem connected with the upper end of said bore.
4. A device of the character described, comprising an elongated flattened body provided with a longitudinal bore, a series of openings between the bore and the front edge of the body, and ducts leading from the openings into the bore and through the front edge of the body, a brush body secured to the body of the device over the openings thereof and extending beyond the front edge of said body, and an intake stem connected with the bore of the body.

In testimony that we claim the foregoing as our invention we have signed our names this 13th day of November, 1928.

HERBERT HENRY HARRIS.
